(57) **CLAIM**

The ornamental design for a combination work light and spotlight as shown and described.

DESCRIPTION

FIG. 1 is a top perspective view of the combination work light and spotlight design;

FIG. 2 is a bottom rear perspective view of the combination work light and spotlight shown in use thereof;

FIG. 3 is a top view of the combination work light and spotlight shown in use thereof;

FIG. 4 is a bottom view thereof;

FIG. 5 is a left side perspective view thereof;

FIG. 6 is a right side perspective view of the combination work light and spotlight shown in use thereof;

FIG. 7 is a front perspective view thereof;

FIG. 8 is a rear perspective view of the combination work light and spotlight shown in use thereof;

FIG. 9 is a top perspective view of the open configuration of the combination work light and spotlight design;

FIG. 10 is a bottom of the combination work light and spotlight shown in use thereof;

FIG. 11 is a top view of the combination work light and spotlight shown in use thereof;

FIG. 12 is a bottom view of the combination work light and spotlight shown in use thereof;

FIG. 13 is a left side perspective view of the combination work light and spotlight shown in use thereof;

FIG. 14 is right side perspective view of the combination work light and spotlight shown in use thereof;

FIG. 15 is a front perspective view of the combination work light and spotlight shown in use thereof; and,

FIG. 16 is a rear perspective of the combination work light and spotlight shown in use thereof.
